UNITED STATES PATENT OFFICE

NELS T. NELSON, OF ATTLEBORO, MASSACHUSETTS, ASSIGNOR TO J. F. STURDY'S SONS CO., OF ATTLEBORO FALLS, MASSACHUSETTS, A CORPORATION OF MASSACHUSETTS

CHAIN

Application filed May 31, 1930. Serial No. 458,645.

This invention relates to a chain, particularly the type used for a bracelet to hold the wrist watch in place on the arm of the wearer, and has for its object to provide a construction which will be strong and durable, attractive in appearance, and in which the parts may be easily formed in multiple by machine operations.

A further object of the invention is to provide means for connecting the main body links at spaced points and yet provide a construction which is extremely flexible to shape itself to the wrist for ease and comfort in wear.

15 A still further object of this invention is the provision of means for spacing the connections between the main body links in order that they may maintain their desired position in the bracelet.

20 With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a top plan view of a plurality of links connected together in series;

30 Fig. 2 is a section on line 2—2 of Figure 1;

Fig. 3 is a perspective view of the body link;

Fig. 4 is a perspective view of the connecting link; and

35 Fig. 5 is a section on line 5—5 of Figure 1.

It is found in the use of bracelets for retaining a watch on the arm of the wearer that the same must fit snugly about the wrist, causing perspiration to form beneath the bracelet, especially in warm climates, causing the acids of the skin to discolor the bracelet and providing a condition for the ready accumulation of dust to soil the wrist, and in order to provide for a circulation of air about the wrist and to prevent in a large measure the above undesirable results, bracelets have been formed having links of open rectangular shape to permit a maximum of

circulation of air to reach the portions of the skin beneath the bracelet, and in order that a strong and durable structure may be formed of handsome appearance, I have provided separate connecting links to encircle the adjacent ends of the body or main links and notched the end bars to receive these connecting links so that the inner edge of the connecting links will lie substantially flush with the edge of the body link leaving an opening of regular appearance, and by reason of these notches the connecting links are held spaced from each other, thereby maintaining them in their desired relation for obtaining a desired effect of the bracelet; and the following is a detailed description of the present embodiment of this invention, illustrating the preferred means by which these advantageous results may be accomplished.

With reference to the drawings, 10 designates the main or body link generally of open rectangular shape having side bars 11 and end bars 12. The end bars 12 are notched as at 13 to receive in these spaced notches the connecting links 14, as illustrated in Figures 1 and 2. The connecting links are of a thickness substantially the depth of the notches 13 so that their outer surface 15 will lie flush with the inner edge 16 of the end bar of the body link to form an opening having a regular formation substantially rectangular in shape through the chain of a more finished and more attractive appearance than were the shape of this opening broken by the connecting links 14 protruding into the opening. The portion 17 between the notches 13 serves as a means for spacing the pair of connecting links 14 which encircle the adjacent end bars 12 of each of the body links, and although I have shown two or such connecting links, any desired number may be used depending upon the width of the construction and the appearance desired for the chain.

The top surfaces 18 of the body links are rounded, as illustrated in Figure 5, which rounding assists the same in conforming to the curvature of the connecting links when in position. The top surface of the chain may be ornamented in any desired design,

while the connecting links may be left plane, and being raised in relief from the surface of the body links may have a finish to contrast with the ornamentation of the body links to relieve a monotony of appearance and cause the same to be more pleasing to the eye.

While I have described certain construction forms which embody the principles of my invention, it is obvious that other desired changes in arrangement may be made within the spirit and the scope of the invention as defined in the appended claims.

I claim:

1. A chain comprising a series of body links generally rectangular in shape having opposite side and end bars, said end bars having notches therein, a plurality of separate connecting links embracing the adjacent end bars of the body links, and located in said notches for hingedly connecting them together.

2. A chain comprising a series of body links generally rectangular in shape having opposite side and end bars, said end bars having notches therein, a plurality of separate connecting links embracing the adjacent end bars of the body links, and located in said notches for hingedly connecting them together, said connecting links having a thickness substantially the depth of said notches, whereby the inside edge of said body links lies substantially flush with said connecting links.

In testimony whereof I affix my signature.

NELS T. NELSON.
